(74) Attorney, Agent, or Firm — Banner & Witcoff, Ltd.

(57) CLAIM

The ornamental design for a sandbag, as shown and described.

DESCRIPTION

FIG. 1 is a top, front, perspective view of a sandbag showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear, bottom perspective view thereof.

The “ROGUE” logo shown in broken lines forms no part of the claimed design.

1 Claim, 8 Drawing Sheets(56)
